FIG.2

FIG.1

FIG.3

FIG. 1 is a front elevational view of a ball-point pen, showing my new design.

FIG. 2 is a top plan view thereof.

FIG. 3 is a side view thereof.

My design comprises a relatively flat pen formed by enclosing a ball-point cartridge within two pieces of plastic which are seamed at their edges, substantially as shown.

I claim:

The ornamental design for a ball-point pen or similar article, substantially as shown and described.
